UNITED STATES PATENT OFFICE.

DAVID LANCASTER DWINNELL, OF MONTREAL, CANADA.

HEATING APPARATUS.

SPECIFICATION forming part of Letters Patent No. 687,300, dated November 26, 1901.

Application filed October 14, 1897. Serial No. 655,191. (No model.)

To all whom it may concern:

Be it known that I, DAVID LANCASTER DWINNELL, a citizen of the United States, and a resident of the city of Montreal, Province of Quebec, Dominion of Canada, have invented certain new and useful Improvements in Heating Apparatus; and I do declare that the following is a full, clear, and exact specification and description of the same.

10 The object of my invention is to increase the efficiency of heating apparatus by the more complete combustion of the fuel consumed and applying the heat generated to the greatest advantage. I obtain this result by means of a new system, in which the gases from the fire-box are drawn off, mixed with air, and then fed to the fire through an up-draft-grate which forms one portion of the fire-bed, then down through the other portion, 20 which is a downdraft-grate, and over a combustion-chamber which connects with the outlet. An air-supply around the edge of the grate feeds the fuel with the necessary quantity to produce complete combustion.

25 In order to illustrate my invention, I will describe the application of it to an ordinary return-flue boiler. It is equally applicable to other styles of boilers, furnaces, stoves, and other forms of heating apparatus.

30 Reference is made to the annexed drawings, in which like signs represent like parts.

Figure 1 is a sectional elevation across the grate, being on the line X X of Fig. 2. Fig. 2 is a plan view on the section-lines R R and S S, respectively, of Fig. 1. Fig. 3 is a sectional elevation on the line Z Z, Fig. 1. Fig. 4 is a sectional elevation on the line Y Y of Fig. 1.

The boiler 10 is bricked up at 2 from the 40 grate-level upward and forms a front compartment 1^a over the fire-box 1 with the walls 1^b 1^c. Beneath the grate the walls 4^a 4^b divide the space into three compartments, the middle one of which, 4, is closed at the end by 45 an extension 2^a of the wall 2, while the side compartment 1^a connects with the flame-bed 11. A flue 3 connects the upper part of the compartment 1^a with the mixing-chamber 4, an air-supply entering this flue at 9. Around the 50 grate are air-feed openings 8.

The manner in which the apparatus oper-

ates is as follows: The gases arising from coal placed on the grate pass off and down the flue 3 and, with the additional air which is added at 9, into the mixing-chamber 4. They 55 are then drawn up through the grate-bars 5 and down through the incandescent fire on the bars 6, which I prefer to be water-bars, as shown in the drawings, having the divided header 6^a, bends 6^b, inlet-feed from boiler 6^c, 60 and outlet-return to boiler 6^c. The flame thus produced is carried under the wall 2 to the flame-bed 11, and thence through the tubes of the boiler. The draft which draws the gases and air down through the grate 6 also draws 65 air from the openings 8, and the result is the complete combustion of the fuel and the combustible gases. Only the incombustible gases are given off. Suitable dampers 8^a, 9^a, and 13 control the air-inlets and chimney-draft, 70 respectively. All the air fed to the fire passes through the fire, and the combustion of the gases which it is mixed with is most complete. The smoke and gases which are drawn off by the flue 3 can be collected and used 75 separately and air alone or gases from another source fed under the grate 5.

By means of this apparatus a great economy in fuel is obtained and the highest efficiency in heating and a smokeless outlet are 80 arrived at.

The draft-circuit from fire-box to mixing-chamber is perfectly independent of and distinct from the chimney-draft.

The air-supply around the grate is arranged 85 to be easily regulated to supply the demands of the downdraft-fire.

The flame which passes under the middle wall, in addition to the air entering through the mixing-chamber, is a transparent and 90 clear flame and carries with it a minimum of solid matter.

Having now described my invention, what I claim as new, and desire to secure by Letters Patent, is—

1. A heating apparatus comprising a fire-grate, a mixing-chamber connected with the under side of a portion of such grate, a passage connecting the space above such fire-grate with such mixing-chamber, a passage 100 down through the other portion of the said grate connecting with outlet, and an air-sup-

ply to such mixing-chamber for the purposes set forth.

2. A heating apparatus comprising a fire-grate, a mixing-chamber connected with the 5 under side of a portion of such grate, a passage connecting the space above such fire-grate with such mixing-chamber, an air-supply connected to such passage, an opening from mixing-chamber to surface of grate, a 10 passage down through the other portion of said grate connecting with the outlet for the purpose set forth.

3. A heating apparatus comprising a fire-grate, a mixing-chamber connected with the 15 under side of a portion of such grate, a passage from above grate, connecting with mixing-chamber, an air-supply to mixing-chamber, a passage down through the other portion of said grate connecting with the outlet and 20 an air-supply on the level of the fire.

4. A heating apparatus comprising a fire-grate, a mixing-chamber connected with the under side of a portion of such grate, a passage from above such grate to such mixing- 25 chamber, a supply of heated air to such passage, a passage down through the other portion of such grate, connecting with the outlet for the purpose set forth.

5. A heating apparatus comprising a body 30 portion of suitable form, a fire-grate, a mixing-chamber beneath a portion of such grate and draft-circuits from space above grate

to mixing-chamber and from above grate through the grate to the chimney as set forth.

6. A heating apparatus comprising a body- 35 portion containing a fire-grate, a mixing-chamber, an air-inlet on level of such grate, a passage connecting space above grate with mixing-chamber, an air-supply thereto, a draft-circuit from above grate to mixing- 40 chamber, and from above grate through grate to outlet as set forth.

7. A heating apparatus consisting of a grate, mixing-chamber, a combustion-chamber leading to outlet, a flue from above grate to mixing-chamber, an air-inlet to flue, one portion of grate over mixing-chamber adapted to an updraft, the other portion of grate over combustion-chamber adapted to a downdraft, and an air-supply from outer edges of grate. 45

8. A heating apparatus consisting of a grate, a mixing-chamber, a combustion-chamber leading to outlet, a flue from above grate, an air-inlet to mixing-chamber, one portion of grate over mixing-chamber adapted to an up- 50 draft, the other portion over combustion-chamber, adapted to a downdraft, and an air-supply from edges of grate.

Signed in the presence of the two undersigned witnesses.

DAVID LANCASTER DWINNELL.
